United States Patent Office

Des. 177,349
Patented Apr. 3, 1956

177,349

LINK CHAIN BRACELET OR THE LIKE

Jeanne Allen Sharp and Sherie Kent Spitz, Brooklyn, N. Y., assignors to Flex-Let Corporation, East Providence, R. I., a corporation of Rhode Island

Application February 16, 1955, Serial No. 34,544

Term of patent 7 years

(Cl. D45—4)

FIG. 1

FIG. 2

FIG. 3

Parts of the bracelet have been broken away for convenience of illustration.

We claim:

The ornamental design for a link chain bracelet or the like, substantially as shown and described.
